United States Patent

Des. 238,536
Patented Jan. 27, 1976

238,536

STORAGE DRAWER

Robert K. Scherzer, Liverpool, N.Y., assignor to Gaylord Bros., Inc., Liverpool, N.Y.

Filed Oct. 15, 1974, Ser. No. 514,936

Term of patent 14 years

Int. Cl. D6—06

U.S. Cl. D6—191

FIG. 1

FIG. 2

FIG. 3

FIG. 4

FIG. 5

FIG. 1 is a perspective view of the storage drawer, embodying my new design;

FIG. 2 is a top plan view thereof;

FIG. 3 is a side elevational view of the drawer wherein a portion thereof has been broken away for convenience of illustration;

FIG. 4 is a cross-sectional view thereof; and
FIG. 5 is a bottom plan view thereof.

I claim:

The ornamental design for a storage drawer, as shown and described.
